UNITED STATES PATENT OFFICE

105,824

DESIGN FOR A STATUETTE

Joe Romano, Des Moines, Iowa

Application January 26, 1937, Serial No. 67,291

Term of patent 14 years

To all whom it may concern:

Be it known that I, Joe Romano, a citizen of the United States, and a resident of Des Moines, in the county of Polk and State of Iowa, have invented a new, original, and ornamental Design for a Statuette, of which the following is a specification, reference being had to the accompanying drawing, forming part thereof,

I claim:

The ornamental design for a statuette, substantially as shown.

JOE ROMANO.
